Inventor:
Herbert O. Crippen.

Be - Son of Bain Hinckley (HHS)

UNITED STATES PATENT OFFICE.

HERBERT O. CRIPPEN, OF SANFORD, FLORIDA.

PHONOGRAPH.

Application filed November 17, 1921. Serial No. 515,806.

To all whom it may concern:

Be it known that I, HERBERT O. CRIPPEN, a citizen of the United States, residing at Sanford, in the county of Seminole and State of Florida, have invented certain new and useful Improvements in Phonographs, of which the following is a specification.

This invention relates to improvements in phonographs.

10 One of the objects of the invention is to generally improve phonographs or so-called talking machines.

15 A more specific object of the invention is to provide an improved amplifying casing or horn containing a double tone chamber.

20 Another object is to provide an improved casing, enclosing a tone chamber, which is responsive to the high and to the low notes with utmost fidelity, and which is resonant 25 to an extent that it increases the volume or tone and reinforces all tones, equally vibrating in the same time.

25 Another object is to provide a vibratable casing enclosing a tone chamber and another relatively rigid spaced away casing enclosing the vibratable casing, leaving a sealed space intervening between the two casings, to thereby provide a resonant chamber outside of the usual sound amplifying 30 horn.

35 Another object is to provide a sound responsive casing containing a tone chamber and means to tension the chamber, thereby to make it more sensitive to normally inaudible sound emanating from the amplifying casing or horn.

40 Another object of the invention is to improve the cabinet and arrangement of the horn and sound reproducing instrumentality to render scratching of the needle less apparent.

Other objects and advantages of the invention will hereinafter appear.

In the drawings:—

45 Fig. 1 is an isometric perspective view of the double casing sound amplifier and modifier containing an inner and an outer tone chamber showing parts in section.

50 Fig. 2 is a front elevation of an improved cabinet in one side of which the improved devices are to be contained.

Fig. 3 is a section taken on line 3—3 of

Fig. 2.

55 Fig. 4 is a section taken on line 4—4 of Fig. 3.

Fig. 5 is a longitudinal section of the horn or amplifier with the closed and sealed tone chamber, on the vertical sides only, being omitted from the top and bottom.

Fig. 6 is a longitudinal section of the 60 modification of the device shown in Fig. 1.

In all the views the same reference characters are employed to indicate similar parts.

The sound amplifying and improved resonant structure shown in Fig. 1 and several of the other figures, consists of the inner casing 10 enclosing a tone chamber 11. The inner wall 10 is preferably made of close grain well seasoned spruce, pine, or other suitable responsive material. The casing 10 is not unlike that which usually is used in the best of phonographs, and may be made of any material best adapted for the purpose. The vibratable casing 10 is surrounded by an outer casing 12 spaced 65 away therefrom to enclose an outer tone chamber 13. The outer wall 12 is preferably thicker than the wall 10 and is made of thoroughly seasoned maple or other hard wood to afford a substantially non-vibratable backing to reflect the sound into the inner chamber 11. The casing 10 is provided with openings 14 which may be of any suitable shape, in the form of a scroll as shown, or in any other suitable form thru 70 which the outer tone chamber 13 communicates with the inner tone chamber 11. The inner wall 10 of the inner casing is tensioned by means of the tone posts 15 which are placed between the walls 10 and 12, and which hold the former wall under tension 75 just as a similar tone post is placed in a violin to render it more sensitive to sound vibration.

The two casings, 10 and 12, are sealed together at their ends, as at 16 and as at 17, and in some instances to the side wall 10 is open into the interior of the tone chamber 11; thus the sound vibration, or waves of sound, are passed thru the wall of the chamber 11 into the outer tone chamber 13, and the waves of sound, or tone, are greatly magnified and thrown back in increased volume into the inner tone chamber by the resonant effect of the outer tone chamber and the casing wall between the chambers. 100

105 Of course the size of the device and thickness of the material may be varied to suit other conditions that may present themselves. The voice and other sounds are re- 110

produced in natural deep tones by the device described and as a result of the resonance of the structure, instead of the high pitched metallic tones that are so frequently 5 apparent in devices of this character as ordinarily constructed, and the music of the violin, cello, harp, piano, and other instruments are reproduced in natural tones entirely eliminating the faults heretofore 10 present in phonographs.

In the modification shown in Fig. 6 there are in the outer tone chamber 13 between the walls 10 and 12 a series of vibratable strings 18 secured to the end piece 16 and 15 tensioned by the screws 19. There may be 20 in this chamber as many strings, such as violin or guitar strings, as may be desired that will vibrate in harmony with the casing 10, the sound produced thereby being 25 projected by the back wall 12 into the chamber 11, thru the openings 14. The strings 18 may be tuned to different pitch from the wall 10 and from each other, and they may be of different sizes, so as to be responsive 30 to sound of varying pitch to be projected into the inner tone chamber 11.

The cabinet containing casing 20, shown in section in Fig. 3, has a floor 21, below which the motor for rotating the turntable 30 22 is situated. The tone arm 24 is provided with a downwardly projecting support 25 which is pivoted at 26 about which pivot the arm is movable. It has an upwardly 35 projecting part 27 that is in free unobstructed communication with the throat 28, connected to the smaller end of the horn or tone chamber 11, as at 29. When it is desired to put a needle 30 in the sound box 31 the structure may be moved on the pivot 26 a sufficient distance, laterally off the record that is superimposed from the table 22.

The front of the chamber containing the turntable 22 and the tone arm 24 is normally open, as at 32, capable of being closed by the closure 33, which is hinged at 34 and which is capable of being moved back into the dotted line position, clearly shown, for the purpose of placing a new record upon the turntable, and for inserting a new needle in the sound box.

A curtain 35 is slidable in the groove 36 provided in the cabinet and consists of a number of spaced apart slats 37 having 55 openings 38 therebetween thru which the sound from the horn may pass. The slats are connected together by a cloth 39 glued to the back of the apron. The apron may be moved up from over the larger end of 60 the horn casing to any extent to modify the

sound that will be projected from the tone chamber 11.

In Fig. 5 I have shown a different form of closure for the tone chamber 11 consisting of a curtain 40 contained on a spring roller 41 and may be made of suitable fabric, thru which the sound will issue to some extent, although the curtain may be entirely placed over the full opening of the chamber 11. The roller 41 may operate as a window curtain roller with a suitable pawl and ratchet device by which the curtain 40 may be raised to any extent or entirely removed from the front 70 of the casing 10. 75

The cabinet 20, shown in Fig. 2, may have another compartment for containing records and which may be closed by a curtain 42 which is similar to the curtain 37, as more clearly shown in Fig. 3. The curtain 37, shown in Fig. 3, may also be drawn to the lower extremity of the opening in the cabinet 20 in a manner similar to the curtain 42 shown on the opposite side of the cabinet, so that both openings in the cabinet 80 may be entirely closed. 85

There is an unobstructed opening from the tone arm thru the inner tone chamber and the tone chamber being above the operating needle and record the scratching produced thereby and the noise of the motor is not carried out thru the horn. 90

One of the additional advantages arising from placing the horn above the record carrying turntable is the availability of the 95 solid top of the cabinet as a table.

While I have herein shown a simple embodiment of my invention with suggested modifications, it is manifest to persons skilled in the art, that considerable other variations may be made, in the general arrangement and configuration of the parts, 100 within the scope of the appended claim.

Having described my invention what I claim as new and desire to secure by Letters Patent, is: 105

A sound amplifying device comprising a thin, yielding, sound-responsive, inner casing, providing a freely open chamber; an outer casing spaced from the inner casing, said outer casing having thick, rigid walls substantially non-responsive to sound vibrations providing a tone chamber between the casings, said intermediate chamber closed at its ends and means between the two casings to tension the thin inner casing. 110

In testimony whereof I hereunto subscribed my name.

HERBERT O. CRIPPEN.
